APPARATUS FOR FEEDING AND CHANGING OF YARNS IN CIRCULAR KNITTING MACHINES

Karel Poláč, Trebic, Moravia, Czechoslovakia, assignor to Zapadomoravské strojírny, národní podnik, Trebic, Czechoslovakia

Application February 28, 1955, Serial No. 490,757

Claims priority, application Czechoslovakia
March 1, 1954

13 Claims. (Cl. 66—140)

The present invention relates to apparatus for feeding and changing yarns on circular knitting machines, more particularly double-cylinder knitting machines used in the automatic manufacture of hosiery goods with course-wise or horizontal stripes of different colors.

In the horizontal striping apparatus used heretofore, the change of yarns takes place in such a way that a selected operative yarn feeder which is to be put out of operation is first withdrawn from its operative position without immediately interrupting the knitting operation being performed with the yarn from this feeder, so as to enable the selected feeder to take up a temporary position wherefrom the yarn is introduced into the needles until the operative feeder is further withdrawn to its retracted position. During this operation, each of the yarn feeders has a different movement imparted thereto in close proximity to the needle latches, as the feeding end of each feeder is at a different distance from the yarn feeding point. For this reason, each of the feeders requires its own operating cam, as well as its own catch wheel with pawl and control device and its own trapping and cutting-off device. Thus, the general layout of the existing horizontal striping apparatus is too intricate and expensive and unreliable, so that the presumed saving in needles and knitting material is not practicable.

It is the object of the present invention to provide an arrangement of the interchangeable feeders and an actuating mechanism for their exchange which are more simple in their constructions than similar arrangements known hitherto, and which, as a result of the simple construction are more reliable in service, can be set in a simple manner to any stripe pattern, and are capable of being manufactured at reduced costs.

To this end, a circular knitting machine suited for course-wise striping and comprising a rotary needle cylinder and a number of interchangeable yarn feeders, has all of its yarn feeders arranged in a plane parallel to the rotary axis of the needle cylinder with the axes of the feeders converging towards the knitting point, and each feeder is guided in a slot of a support for a lengthwise movement as well as for a pivotal movement in a plane through the feeder's axis and at right angles to the plane in which all the feeders lie, and is under the action of a return spring which pulls the feeder into a rest position away from the knitting point. Further, each feeder is provided with a lateral recess adapted to be engaged by a spring biased holding pin, the recess being so located that, when the feeder is shifted into its operational position with its feeding eye at the knitting point, the holding pin engages the recess and maintains the feeder in its operational position. Each feeder is also provided with a longitudinal slot through which a pivot pin extends, and each feeder is associated with a selecting member arranged to be moved against the feeder and to engage it at a point between the pivot pin and the feeding eye so as to deflect the feeder about the pivot pin, while a thrust member is engageable with the end of the feeder remote

2

from the feeding eye when the feeder is in the deflected position in order to shift the feeder towards the knitting cylinder. Further, means are provided to withdraw the holding pin from the feeder in the operational position to allow this feeder to return into its rest position under the action of its return spring, the arrangement being such that, after the holding pin of the operational feeder is withdrawn, the selecting pin of the deflected feeder is released to allow this feeder under the action of its return spring and of its holding pin to swing back into the operational position. The selecting members and the thrust members are advantageously connected together for operation in such a manner that during their operational movement first the selecting member deflects the associated feeder about its pivot pin so as to bring its end remote from the eye into the range of the thrust member, that thereafter the thrust member shifts the deflected feeder towards the needle cylinder against the action of the return spring, that the thrust member then engages the means for withdrawing the holding pin from the operational feeder, and that, with the return movement of the thrust member, selecting member also returns and allows the selected feeder to swing back to assume its operational position.

Further advantages and features of the present invention will be apparent in the following detailed description with reference to the accompanying drawings illustrating by way of example an embodiment of a five feeder striping attachment on a double-cylinder knitting machine.

30 In the drawings:

Fig. 1 shows on an enlarged scale a vertical section of the needle cylinders along the plane 4—4 in Fig. 4 and an elevational view of the yarn feeder layout with respect to the needle cylinders during normal knitting;

35 Fig. 2 is a partial plan view of the structure shown in Fig. 1;

Fig. 3 is a horizontal sectional view of the yarn feeding and changing apparatus along the plane 6—6 in Fig. 6 during the change of the individual feeders;

40 Fig. 4 is a plan view like Fig. 2, but showing the feeder selection and feeder operating device, as well as the yarn engaging, trapping and cutting devices;

Fig. 5 is an elevational view of a portion of the device as viewed in the direction of the arrow "2" in Fig. 4;

45 Fig. 6 is a lateral view of the yarn feeding and changing device as viewed in the direction of the arrow Z₁ in Fig. 5, but with the feeder selecting and the feeder operating devices having been omitted;

Fig. 7 is a perspective view, on an enlarged scale, of a detail of the selecting device for the striping feeders;

50 Fig. 8 is a developed view of the pin drum, showing by way of example an arrangement of the selecting pins in the selecting holes;

Fig. 9 is a perspective view, on an enlarged scale, of a detail of the selecting device for the heel feeder;

55 Fig. 10 is a perspective view, on an enlarged scale, of the change-over mechanism of the feeder selecting device;

Fig. 11 is a side view of the devices shown in Fig. 4 as viewed in the direction of the arrow Z₂ in Fig. 4 during normal knitting, but with the yarn feeding and yarn changing device having been omitted;

60 Figs. 12 to 17 are plan views similar to that of Fig. 4, but showing only those parts required for an understanding of the change of two striping feeders;

65 Fig. 18 is a side view similar to that in Fig. 11 but during knitting of the heel or toe;

68 Figs. 19 and 20 are plan views similar to that in Fig. 4, but showing only those parts required for an understanding of the exchange of a striping feeder for a heel feeder;

70 Fig. 21 is an elevational view on a reduced scale similar to that in Fig. 5, but without the yarn feeding and

changing device, and showing a control mechanism for the feeder selecting drum during normal knitting;

Fig. 22 is partly a horizontal sectional view along the plane 21—21 in Fig. 21 and partly a plan view of the structure in Fig. 21, but with the yarn feeding and changing device having been omitted;

Figs. 23, 24 and 25 are fragmentary side views as viewed in the direction of the arrow Z_3 in Fig. 21, at different periods of action of the central control device;

Fig. 26 is a plan view on a reduced scale of the straightened timing chain in Fig. 21 with links for a normal feeder change;

Fig. 27 is a plan view similar to that in Fig. 26, but with chain links for any required feeder change;

Fig. 28 is a fragmentary elevational view of the yarn 15 engaging, trapping and cutting device as viewed in the direction of the arrow Z_4 in Fig. 4; and

Figs. 29 to 33 are fragmentary elevational views of the cutting device as viewed in the direction of the arrow Z_5 in Fig. 4, but showing different operational positions 20 during the change of two feeders.

Figure 34 is a side view of the heel yarn drawing-off device as viewed in the direction of the arrow Z_6 in Figure 5, during normal knitting;

Figure 35 is a horizontal section along the plane 34—34 during normal knitting and knitting of the heel or toe.

The yarn feeding mechanism of a circular machine for producing course-wise or horizontal stripes comprises, as can be seen best in Figs. 4, 21 and 22, a yarn feeding and interchanging device A, a striping feeder selecting device B, a heel feeder selecting device C, a change-over device D for both selecting devices B and C, a common feeder operating device E, a central control device F, a control mechanism G for the pin drum, a yarn trapping and cutting-off device H, a further yarn cutting-off device K and a yarn engaging device M.

The yarn feeding and interchanging device A as shown in Figs. 1, 3, 4 may comprise any required number of movable yarn feeders, for example, the five feeders indicated in the illustrated embodiment by the reference numerals 1, 2, 3, 4, 5. These feeders can be selected individually and serve for feeding one or several yarns 6, 6a or 6b (Figs. 2, 3, 19) into double-ended latch needles 7 of a circular knitting machine having superimposed bottom and top needle cylinders 8 and 9. The longitudinal axes 10 of the individual feeders converge radially towards a common feeding point 11 located on the horizontal axis of the central feeder 3 near the needle cylinders, but just outside the path of the closing latches of the needles. When the feeders are in their normal inoperative position, then feeding eyes are spaced from the feeding point 11 by the same distance. All the feeders 1 to 5 are of rectangular cross section (Fig. 2) and of the same size, and further are arranged one above the other. Each feeder has a longitudinal slot 14 (Fig. 3) through which a pivot pin 30 extends, the pin 30 being in the form of a wire and being common to all of the feeders. Thus, each feeder forms a double-armed lever, and the arm remote from the feeder eye has a lateral recess 15 and a rounded end 16 which is connected by a spring 12 to a common feeder guard 13. The feeders 1 to 4 serve for horizontal or coursewise striping the leg and sole of the stocking, while the topmost feeder 5 serves for knitting the heel and toe or the reinforced upper part of the stocking. For the manufacture of ribbed hosiery, the feeders can be provided with two yarn feeder eyes.

All the feeders are arranged in a slidable and pivotal manner in convergent radial grooves 18 of a common support 19 (Fig. 4) and are secured laterally by means of a removable plate 20. Each feeder is associated with two pins, namely a selecting pin 21 and a holding pin 22, which pins are arranged to engage the edge of the related feeder (Fig. 4). The pins 21 and 22 are guided for axial displacement in bores of the support 19, and,

as shown in Fig. 6, the bores which accommodate the selecting pins 21 are situated along a section of a circle which has its center at the point 11 and a radius x , while the bores accommodating the holding pins 22 are arranged along a section of a concentric circle having the larger radius y . When the feeders 1 to 5 are in their normal positions, their edges facing the pins 21 and 22 are located in a vertical plane 3—3 (Fig. 5) extending in parallel relationship to the longitudinal axis of needle cylinders 8 and 9. The end of each holding pin 22 is urged by a spring 23 to engage in the lateral recess 15 of the respective feeder (Fig. 3). Each spring 23 bears against the enlarged head of the related holding pin 22 as well as against a plate 24 fixed removably on the support 19. Parallel with, and symmetrically with respect to, the horizontal longitudinal axis 10 of the central feeder 3, two inclined slot-like grooves 25 (Figs. 4, 5, 6) are cut into the support 19 and receive abutment wedges 26 of a comb 27 which, in turn, is slidably supported on pins 28 of the plate 24 and urged in a direction toward the feeders by springs 29 surrounding the pins 28. The comb 27 thus serves for actuating the holding pins 22.

Each selected feeder assumes during its operation, 25 successively and independently of the other feeders, five different positions I, II, III, IV, V (Fig. 3) located in a plane at right angles to the needles and outside the range of the needle latches. The rest or non-feeding position I of all feeders is secured by the pivot pin 30 (Figs. 3, 6) 30 which is provided in the support 19 and extends in the form of an arc through all the longitudinal slots 14 of the feeders 1 to 5, and is provided at its end outside support 19 with an adjustment ring 31 (Fig. 6). The intermediate positions III, IV and the operative or normal feeding position V are secured by the engagement 35 of the holding pin 22 in the recess 15 of the respective feeder (Figs. 3, 14, 16).

The selecting device B for the striping feeders comprises a selecting drum 32 (Fig. 7) rotatably mounted 40 on a shaft or axle 33 supported by a bottom selecting lever 34, which in turn is pivotally supported on a pivot pin 35 of a bracket 36 (Fig. 4). The selecting drum 32 has a surface forming a regular polygon which, in the illustrated embodiment has twelve faces (Fig. 8) each 45 provided with a row of bores 37 which is intended to co-operate with one of the four feeders 1 to 4 by receiving the bevelled end of a selecting pin 21. The bores 37 of each row are arranged along a section of a circle with the radius x' , which is the same as the previously 50 mentioned radius x .

In one of the bores 37 of each face of drum 32 there is an interchangeable selecting pin 38 (Figs. 9, 11) for co-operating with the corresponding selecting pin 21 (Fig. 12). The selecting drum 32 is coupled with a ratchet 55 wheel 39 (Fig. 7) with a number of teeth equalling the number of the drum faces. Between the teeth of the ratchet wheel 39 a tooth 41 of a pawl 42 can be engaged under the action of a spring 40 (Fig. 21), the pawl 42 being supported pivotally on a screw 43 of the bracket 36 60 (Fig. 4). The free end of pawl 42 is provided with an extension 44. A spring 45 provided inside the selecting drum 32 on the axle 33 brakes the rotary movement of the drum (Fig. 11).

The selecting device C for the heel feeder 5 consists, 65 as can be seen in Figs. 9 and 19, of an arm 46 fixed adjustably by means of screws 47 on an upper selecting lever 48 and adapted to co-operate with the respective selecting pin 21 of the heel feeder 5 (Figs. 19, 20). The lever 48 is supported pivotally on the pivot pin 35 of the bottom selecting lever 34.

The change-over mechanism D (Fig. 10) which determines whether the selecting device B for the striping feeders 1 to 4 or the selecting device C for the heel feeder 5 is to be actuated, consists of a change-over 70 member 49 supported rotatably in a cam-member 50.

The cam-member 50 is supported pivotally on the pin 35 between both selecting levers 34, 48 (Figs. 4, 11). The change-over member 49 has the shape of a cylindrical disc and is provided with two projections 51, 52 which are shaped and arranged to engage either cylindrical recesses 53, 54 or longitudinal recesses 55, 56 of the selecting levers 34, 48, respectively (Figs. 7, 9, 10). Each cylindrical recess 53 or 54 opens at a point into the associated longitudinal recess 55 or 56. The change-over member 49 is provided with an adjustment pin 57 guided in a horizontal slot 58 of the member 50 as well as in an inclined slot 59 of a guide plate 60 (Fig. 11). Both projections 51, 52, are arranged symmetrically with regard to the vertical axis of the change-over member 49 and to the horizontal axis of the adjustment pin 57 in such a way that the top projection 52 is above the member 49 and pin 57 and the bottom projection 51 is beneath the member 49 and pin 57 (Fig. 4). The cam-member 50 carries in a lateral recess 61 (Fig. 10) a holder 62 (Figs. 12, 21) with two shoulder screws 63 which project through two inclined slots 64 of the guide plate 60 and thus permit this plate to be vertically and horizontally displaced within certain limits (Figs. 11, 18). A spring 67 is suspended from a bracket 65 fixed on the holder 62 and from a screw 66 on the guide plate 60. A bevelled corner 68 of the guide plate 60 co-operates with the bent end of an intermediate member 69 attached to the bent end 70 of an actuating lever 71, in order to control a clutch 72 required for the knitting of the heel and toe (Figs. 21, 22). The selecting levers 34, 48 are urged into their inoperative positions by springs 73, 74 which are connected at one end to the levers 34, 48 and, at their other end, to a holder 75 of the bracket 36 to move the selecting levers towards adjusting screws 76 of a post 77 (Figs. 4, 19).

The common feeder operating device E as shown in figs. 4 and 5 comprises an operating lever 78 for the feeders 1 to 5, said lever carrying on an adjustable pin 79 a roller 80 in rolling contact with a concave camway 81 on the member 50. The lever 78 is fixedly connected to a spindle 82 of the bracket 36. A thrust plate 83 provided at laterally extended branches 84 of the lever 78 has an arcuate shape with a part circular cross section having the radius y corresponding to the radius y of the circle centered at the feeding point 11 (Fig. 6) and on which the rounded ends 16 of all feeders are situated when the feeders assume the position IV (Fig. 14). A lever 85 (Fig. 21) is fixed to the lower end of the spindle 82 below the bracket 36 and is connected with a lever 87 by means of a link or pull rod 86, the lever 87 being fixed to the top end of a spindle 88 supported in a bearing of the frame member 89.

The central control device F comprises, as can be seen in Fig. 22, a cylindrical actuating drum 90 with a curved cam groove 91 engaged by a roller 92 carried by the longer arm of a double-armed lever 93. The lever 93 is pivotally supported on a pin 94 fixed in the lower flattened end of the spindle 88 (Fig. 21). The cam groove 91 has a straight portion in which a lobe 95 is situated (Figs. 21, 23). One revolution of the grooved drum 90 mounted on an intermediate shaft 96 corresponds to one revolution of the needle cylinders 8, 9. The shorter arm 97 of the lever 93 engages in a recess 98 of a frame 99 fixed on the part 89 of the machine frame. A spring 101 is connected between the arm 97 of the lever 93 and a spring carrier 100 on the spindle 88. The arm 97 of the lever 93 is held in the recess 98 by a tooth 102 of a slide 103, and the latter is guided by pin screws 104 in oblong holes 105 of the frame 99. A spring 106 is suspended on a screw 107 of the frame 99 and on a screw of the slide 103 to hold the latter in its locking position. A pusher member 108 co-acts with the slide 103 and is supported pivotally on a screw 109 (Fig. 22) of a holder 110 fixed on the frame member 89 (Fig. 21). An adjusting nut 112 is pivotally mount-

ed on a pin screw 111 of the pusher member 108 and screwed into the nut 112 is the end of a connecting rod 113 which is provided with adjustment members 114, 115. The other end of connecting rod 113 is connected, by means of a screw 116, to one arm of a double-armed lever 117 which is freely rotatable on a shaft 118. A cam follower 119 is fixed to the other arm of the lever 117 to slide over cam members 121 which project from some of the links of a chain 120 and which are all of the same height (Fig. 26). A spring 122 suspended at one end from the adjustment member 114 and at its other end from a holder 123 maintains the pusher member 108 in its inoperative position (Fig. 22) and the cam follower 119 in contact with the cam members 121 on chain 120. The adjusting member 115 bears against a part of the machine frame 124 and limits the stroke of the connecting rod 113 when the cam follower 119 slides over the cam members of the chain 120 (Fig. 21).

For controlling the mechanism G of the selecting drum 32 (Fig. 22) some links 125 of the chain 120 are provided with one laterally projecting stud 126, while other chain links 127 have two laterally projecting studs 126 (Fig. 27) which are interconnected with the chain links 120 in accordance with a pre-determined order. A cam follower 128 rides over the laterally protruding studs 126 and is carried by one arm of a double-armed lever 129 which is likewise angularly displaceable on the shaft 118 (Fig. 21). A connecting rod 131 is connected, by means of a screw 130, to the other arm of the lever 129 and carries, at its other end, an adjusting nut 132 connected by means of a screw 133 with a lever 134 supported pivotally on a screw 135 of the holder 110. A tie rod 136 hinged at the free end of the lever 134 is connected with a double-armed lever 137 supported pivotally on a screw 138 (Fig. 22) of the bracket 89. The free end of the lever 137 cooperates with an extension 139 of a nut 140 (Fig. 11) screwed on a threaded prolongation or extension of the axle 33 which carries the selecting drum 32. A spring 141 (Fig. 22) connected at one end to an adjustable bracket 142 fixed to the rod 131 and at its other end to the holder 123, serves for maintaining the engagement between the cam follower 128 and the lateral studs 126 of the chain links 125, 127 (Fig. 27).

The yarn trapping and cutting-off device H as illustrated in Figs. 4, 11, 28 is common to all yarns 6, 6a, 6b of the feeders 1 to 5 is formed by a fixed trapper jaw 143 secured by a pin 144, which pin is adjustably mounted in a holder 145 of the bracket 36 and secured by a nut 146. The trapper jaw 143 is provided with three horizontal grooves 147 for engagement with pivotally mounted trapper jaws 149. The movable jaws 149 are pressed against the stationary jaw 143 by the extended portion 150 of a torsion spring 151 which is held by a screw 152, so that the yarns are safely held between the jaws. Each trapper jaw 149 is urged individually against the bottom of the respective groove 147 by the prong of a common fork-shaped blade spring 153, the latter as well as a yarn guide 154 being fixed by means of a shoulder screw 155 to the wall of the trapper block 143 which faces the feeders 1 to 5 (Fig. 28), with the prongs of the blade spring 153 extending over the transversely extended portion 150 (Fig. 29) of the torsion spring 151. To the other side wall of the trapper block 143 a stationary cutting blade 157 is fixed by means of a screw 156 for co-operation with a movable cutting blade 158. The cutting blade 158 is in the form of a two-armed lever which is pivotally supported on a pivot screw 156 and urged against the stationary cutting blade 157 by the action of a torsion spring 160 (Fig. 4). The cutting blade 157 is provided, at its rear end, with an actuating pin 159 (Fig. 29) which is guided in a longitudinal slot 161 of a lever 162 supported pivotally on a pivot screw 163 of a bent bracket 164. The bracket 164 and its support 145 are fixed to the frame member

36 by means of screws 165. A spring 166 connected to the lever 162 and to the bracket 36 holds the moveable cutting blade 158 in its closed condition (Figs. 29 to 32). An actuating latch 168 in the shape of a bell-crank lever is pivotally mounted on a screw 167 of the lever 162 and co-operates with a cam member 169 fixed adjustably on a link 170. A spring 171 connected, at one end, to the actuating latch 168 and, at the other end, to the lever 162 holds the actuating arm 172 of the latch 168 in a vertical position (Fig. 29). A screw 173 (Fig. 4) connects one end of the link 170 with a lever 188, while an adjustable pin 174 connects the other end of the link 170 with a lever arm 175 fixed adjustably on the spindle 82 of the frame member 36.

A yarn cutting-off device K for the yarns 176 and 177 (Fig. 17) comprises a stationary cutting blade 178 and of a movable cutting blade 179 which are operatively interconnected by a pivot screw 180 and mounted on a holder 181 (Fig. 11). An actuating pin 182 of the movable cutting blade 179 carries an adjustment collar 183. A spring 184 connected between the holder 181 and the adjustment collar 183 keeps the movable cutting blade 179 in a closed position. A Bowden wire 185 attached at one end to the lever 162 (Fig. 29) and at the other end to the operating pin 182 of the movable cutting blade 179 is guided in a tube spring 186 (Fig. 11) for transmitting the movement of the lever 162 of the cutting-off device H to the movable blade 179 of the cutting off device K. For removing the cut-off yarn ends 176, 177 out of the machine a trough (not illustrated in the drawings) is fixed on the holder 181.

The yarn engaging device M as illustrated in Figs. 4, 11, 28 comprises a double-armed lever 188 which is pivotally mounted on a pivot pin 144 situated above and spaced from the fixed trapper block 143. A cam follower 190 is pivotally arranged on a pivot screw 189 fixed in the longer arm of the lever 188. A torsion spring 191 supported by the arm of the lever 188 and embracing the follower 190, causes the latter to bear against the edge of a cam plate 192 which is fastened by a nut 193 on the pivot pin 44 which carries the lever 188. The cam follower 190 carries an adjustable yarn guiding element 194, the free end of which moves in a curved path disposed outside the path of the knitting needles 7.

A lever 210 is fixed adjustably on the intermediate member 69 of the actuating lever 71 (Figs. 18, 22) and is provided with a bent end 214 which co-operates with the longer arm of a double-armed latch lever 215 (Fig. 18) supported pivotally on a pivot screw 216 of a bent strip 217 which is fixed adjustably on the axle 33 of the selecting drum 32 by means of a nut 140. The extension 44 of the pawl 42 is engageable with a tooth 218 provided in the shorter arm of the lever 215.

The above described mechanisms operate as follows: During normal knitting, one of the feeders of the yarn feeding and changing device A, for example, the yarn feeder 3, takes up the operative positions V (Figs. 1 to 4) and the remaining feeders 1, 2, 4, 5 are in their rest position I. The yarns 6 are guided in the eyes 17 of the operative feeder 3 and enter tangentially the hooks of the opened latch needles 7, and the radially converging yarns 6a in the yarn guide 154 (Fig. 28) of the inoperative feeders 1, 2, 4, 5 pass transversely over the stationary trapper jaw 143 of the yarn trapping and cutting-off device H. The inoperative yarns 6a, 6b are safely held by the spring-biased movable jaws 149 in the grooves 147 of the stationary jaw 143 (Figs. 4 and 28). The cam follower 119 of the lever 117 of the central control device F rides over the cams 121 of the links 120 of the timing chain (Figs. 21 and 26) so that the pusher member 108 is held in a position away from the slide 103 (Fig. 22). The tooth 102 of the slide 103 holds the arm 97 of the lever 93 in the recess 98 of the frame 99 (Fig. 23) so that the lever 93 assumes the position VI, as shown in Figs. 21 and 22, and, con-

sequently, the roller 92 is outside the cam groove of the actuating drum 90. Thus, the lever 78 of the common feeder operating device E assumes its position O as shown in Fig. 4 wherein its thrust arm 84 is far away from the rounded ends 16, and the roller 80 is away from the cam surface 81 of the cam member 50. The rest position IX of the lever 71 of the clutch 72, as shown in Fig. 22, corresponds to the rest positions XI of the guide plate 60, as shown in Fig. 11, and the inclined slot 59 of the guide plate 60 holds the adjusting pin 57 of the change-over member 49 of the cam member 50 in its position XIII as shown in Figs. 4 and 10. In this position, the bottom projection 51 of the member 49 engages the circular recess 53 of the bottom selecting lever 34 (Fig. 7) whereby the member 49, the member 50 and the lever 34 are connected together. The upper projection 52 engages the longitudinal recess 56 of the upper selecting lever 48 (Fig. 9) so that no operational connection exists between member 50 and lever 48. By the action of the springs 73 and 74, both selecting levers 34 and 48 and cam-member 50 rest on the adjusting screws 76 of the post 77 (Fig. 4) whereby the striping yarn feeder selecting device B and the heel yarn feeder selecting device C are held in their rest position. The selecting drum 32 is in the position KV and the arm 46 is in the position XIX, thus both are in a position away from the selecting pins 21. The tooth 41 of the actuating pawl 42 is free to engage the ratchet wheel 39 of the selecting drum 32 through the action of the spring 40 (Fig. 21), since the latch lever 215, being away from the bent end 214 of the lever 210, assumes the position XXI shown in Fig. 11. The cam follower 128 of the lever 129 of the control mechanism G for the selecting drum 32 has dropped inoperatively between the studs 35 126 which project laterally from the chain links 125 and 127 (Figs. 21 and 27), so that the free end of the lever 137 does not contact the lower extension 139 of the nut 140 of the selecting drum 32 (Fig. 22). The rest position O of the lever 78 of the common feeder operating device E corresponds to the rest position (o) of the yarn guiding member 194 of the yarn engaging device M (Fig. 4) as well as to the position o₁ of the cam member 169 of the tie-rod 170 of the yarn cutting-off device H (Fig. 29), and to the position of the second yarn cutting-off device K shown in Fig. 11. The cutting blades 157 and 158, and the cutting blades 178 and 179 are in their closed positions.

If, for example, the operative feeder 3 is to be exchanged for the inoperative feeder 2 (Figs. 12 to 17), a cam member 121 of the chain link 120 raises the follower 119 of the lever 117 of the central control device F (Fig. 21) whereby the lever 117 is turned so that, through the connecting rod 113, it causes the pusher member 108 to move in a direction towards the slide 103 (Fig. 24). As a result of the action of the pusher member 108 upon the slide 103, the tooth 102 of the latter releases the arm 97 of the lever 93, so that this lever is caused by the spring 101 to turn about the pivot pin 94 from its position VI into the position VII (Figs. 21 and 24). In position VII, the arm 97 no longer engages the recess 98 of the frame 99 and the cam follower roller 92 enters the groove 91 of the drum 90. As a result of a rotation of the drum 90 with the intermediate shaft 96, the inclined portion of the cam groove 91 causes the roller 92 and with it the lever 93 to move into position VIII (Figs. 22 and 25), and the spindle 88 is caused to follow this movement and imparts, through the medium of the levers 85 and 87 and the link 86, a rotary movement to the spindle 82 of the actuating lever 78 of the common yarn feeder operating device E (Fig. 21). As a result, the lever 78 moves from the position O (Fig. 4) into its position P (Fig. 12), while its roller 80 rolls along the cam face 81 of the cam member 50 of the change-over mechanism D, and by so doing deflects the striping feeder selecting device B. The lower selecting

lever 34 together with the selecting drum 32 are turned about the pivot pin 35 of the bracket 36 from the position XV (Fig. 4) in a direction towards the selecting pins 21 into the position XVI (Fig. 12). In view of the fact that the tooth 41 of the operating pawl 42 engages the ratchet wheel 39 of the drum 32 (Fig. 4), the ratchet wheel 39 and the selecting drum 32 are turned in the direction of the arrow on Fig. 12 through one tooth pitch around the spindle 33 during the first half of the above mentioned pivotal movement of the lever 34. During the second half of the above mentioned pivotal movement of the lever 34 and of the lever 78 into the position P, the bevelled ends of the selecting pins 21 enter the related bores 37 provided in the drum 32. One of the bores 37, for example, that which is in the plane of the feeder 2, is provided with the actuating pin 38 which pushes against the selecting pin 21 and the latter in turn engages the feeder 2 to turn the latter about the pin 30 from the rest position I (Fig. 4) into the intermediate position II (Fig. 12). This intermediate position II of each of the feeders 1 to 4 is determined by the related radial groove 18 of the support 19 and by the plate 20. As a result of the turning of the feeder 2, the holding pin 22 is displaced in a direction towards the plate 24. During the operation of the striping feeder selecting device B, the heel yarn feeder device C remains at rest (Fig. 4).

As a result of the pivotal movement of the lever 78 from its position O (Fig. 4) into the position P (Fig. 12), the tie-rod 170 is shifted and its cam-member 169, which actuates the yarn trapping and cutting-off device H, moves from its position o_1 (Fig. 29) into the position P_1 (Fig. 30). Through the action of the cam member 169 upon the tooth 172 of the actuating latch lever 168, the latter is displaced angularly about the pivot 167 without thereby affecting the lever 162 with the movable cutting blade 158. The mentioned movement of the tie-rod 170 also causes turning of the lever 188 of the yarn engaging device M together with the cam follower 190 and the yarn guiding member 194 relative to the cam plate 192 about the pivot pin 144 from the position o (Fig. 4) into the position p (Fig. 12). During further pivotal movement of the lever 78 from its position P (Fig. 12) into the position R (Fig. 13), thrust plate 83 pushes the end 16 of the selected feeder 2 into the intermediate position III (Fig. 13).

The respective yarns 6a, which are held by the trapping device H, are introduced in a tensioned state into the opened latches of the needles 7 which already contain the yarns 6 of the operative feeder 3. During the above mentioned pivotal movement of the lever 78, the contact of the selecting pin 21 of the feeder 2 with the actuating pin 38 of the selecting drum is maintained by the continued engagement between the roller 80 and the side wall 81 of the cam-member 50. During this period, the tie-rod 170 is moved from its position p_1 (Fig. 30) through the position r_1 (Fig. 31) into the position s_1 (Fig. 32) and the lever 188 with the cam-follower 190 and yarn guiding member 194 arrive in the position r (Fig. 13). As a result of further pivotal movement of the lever 78 into the position S (Fig. 14), the feeder 2 is brought into the intermediate position IV, in order to complete the laying of the yarns 6, 6a on some of the needles 7 and the releasing of the operative feeder 3 from its operative position V. Shortly before the lever 78 reaches the position S, the thrust plate 83 pushes against the comb 27, and the wedge-shaped plates 26 of the latter which co-act with the inclined bottoms of the slots 25 of the support 19 cause the comb 27 to move upwards and to the right, as viewed in Fig. 14, so that the comb 27 engages the enlarged heads of the holding pins 22, and thus withdraws the holding pin 22 from the recess 15 of the yarn feeder 3 which is still in its operative position (Fig. 14). Thus, the feeder 3 is released to permit the return thereof under the action

5 of its spring 12 from its operative position V into its rest position I (Fig. 15). The yarns 6 and 6a of the feeders 2 and 3 are, as a result of the knitting action, taken along with the rotating needle cylinders 8 and 9 in a direction indicated by the arrow, and the yarns of the now inoperative feeder 3 are supported by the yarn guide 154. The end 176 of the yarns 6a of the feeder 2 between the needles 7 and the trapping device H forms a loop as a result of the rotation of the needle cylinders, and is drawn, by means of the needles, out of the trapping device H (Fig. 15).

10 During further rotation of the cam drum 90, the cam-follower roller 92 of the lever 93 reaches the portion of the cam groove 91 with opposite inclination and returns the lever 93 from position VIII into the position VII (Figs. 22 and 24) and the spindle 88 is caused to follow this rotary movement. In the position VII the tooth 102 of the slide 103 is pushed in a lateral direction by the arm 97 of the lever 93. The return movement of the lever 93 is transmitted through the medium of the levers 85 and 87 and the link 86 to the spindle 82 of the lever 78, which thus is returned from its position S (Fig. 14) into position R (Fig. 15). During this return movement of the lever 78 in a direction away from the rounded end 16 of the newly introduced feeder 2, the comb 27 returns to its normal position under the influence of both springs 29 (Figs. 5 and 15). Simultaneously, the feeder 2 returns, under the influence of its spring 12, from the intermediate 15 position IV (Fig. 14) into the intermediate position III (Fig. 16) in which the holding pin 22 enters the recess 15 of the feeder 2. During the continued return movement of the lever 78 from the position R (Fig. 15) to the position P (Fig. 16), the tie-rod 170 is also caused 20 to move from the position s_1 in a direction indicated by the arrow in Fig. 32, so that its cam-member 169 moves toward the tooth 172 of the actuating latch 168. The movement of the tie-rod 170 causes a pivotal movement of the lever 188, cam-member 190 and yarn guiding 25 member 194 about the pivot pin 144 from the position r shown in Fig. 15 into the position p shown in Fig. 16. The yarns 6 of the withdrawn feeder 3 are held by the needles 7 and, since they are in a position within the curved path of the yarn guiding member 194, they are 30 engaged by the member 194 and inserted between the 35 trapper jaws of the yarn trapping device H by the movement of the member 194.

35 As a result of the fact that the selection drum 32 is still in its operative position XVI, the yarn feeder 2 is still held in its temporary position III shown in Fig. 16. Further return movement of the lever 78 from the position P (Fig. 16) into the position O (Fig. 17) causes the roller 80 thereof to move away from the cam face of the cam member 50, so that the spring 73 is then 40 capable of returning the bottom selecting lever 34 together with the selecting drum 32 and cam member 50 into their rest position XV, wherein the lever 34 rests against the end of the screw 76, and the selecting pin 21 is released. During the return movement of the lever 45, the tooth 41 of the actuating pawl 42 slides over the teeth of the ratchet wheel 39, which is braked by the spring 45, until the tooth 41 of the pawl 42 comes to lie between two other teeth of the ratchet wheel 39 (Fig. 4). The return movement of the selecting drum 32 causes 50 the latter to release the selecting pin 21 so that the springs 12 and 23 are free to turn the operative feeder 2 about the pin 30 from the intermediate position III (Fig. 16) into the operative position V (Fig. 17). Also 55 as a result of the further return movement of the lever 78 from the position P (Fig. 16) into the position O (Fig. 17), the tie-rod 170 continues its return movement from the position s_1 (Fig. 32) into the position r_1 (Fig. 33), wherein the cam-member 169 engages the tooth 172 of the actuating latch 168. The longer arm of 60 this latch 168 bears against the head of the screw 163

and thus deflects the lever 162 which is provided with the longitudinal slot 161. The actuating pin 159, which engages the slot 161, is caused to follow the movement of slot 161 and thereby imparts to the cutting blade 158 a pivotal movement about the pin screw 156, whereby both cutting blades 157 and 158 of the cutting device H are opened. As a result of the above mentioned pivotal movement of the lever 162 about the screw 163, the wire 185 acts upon the actuating pin 182 of the movable cutting blade 179 of the yarn cutting device K (Fig. 11) causing the blade 179 to turn about the pin 180 and thus to open both blades 178 and 179. The movable cutting blade 158 of the yarn cutting device H lifts the extended end 150, the torsion spring 151 and thereby also the fork-shaped blade spring 153 (Fig. 33) so that only the weight of the movable trapper jaws 149 urge the latter into contact with the grooves 147 of the fixed-jaw or block 143 (Fig. 28). This enables the yarns 6 of the released yarn feeder 3 to be readily introduced between the opened cutting blades 157 and 158, and 178 and 179 of both yarn cutting devices H and K. The tensioned yarns 6 are prepared for the cutting operating. When the cam-member 169 slides over the tooth 172 (Fig. 33) and returns to the position o_1 (Fig. 29), a pivotal return movement of the lever 162 about the pivot pin 163 is brought about by the action of the spring 166, whereby the cutting blades 157 and 158 of the cutting device H are closed. The above mentioned return movement of the lever 162 relieves the wire 185, whereby the spring 184 is allowed to close cutting blades 178 and 179 of the cutting device K (Fig. 11). The yarns 6 of the withdrawn feeder 3 are cut between the trapping device H and the needles 7 at two points so that the free yarn ends 177, which otherwise would be noticeable at the back of the fabric, drop and are removed. The yarn ends 6a of the operative feeder 2, which have been withdrawn from the trapping device H by the movement of the needles 7, also come to lie between the opened blades 178 and 179 of the cutting device K at a point close to the needles, so that the length of the free yarn end 176 is reduced. A trough, not illustrated in the drawings, receives the cut off yarn ends 176 and 177 and serves for their removal out of the range of the cutting devices H and K. After the cutting operation has been completed, the roller 92 which is in the position VII (Figs. 21 and 24) and moves in the cam groove 91 of the actuating drum 90, rides up the lobe 95, whereby it is lifted out of the cam groove 91 into the position VI, in which the arm 97 of the lever 93 is again engaged in the recess 98 of the frame 99 (Fig. 23). Under the influence of the spring 106, the slide 103 is shifted in the direction to cause its tooth 102 to engage and hold firmly the arm 97 of the lever 93 within the recess 98 of the frame 99. The position VI of the lever 93 of the central control device F (Figs. 21, 22, 23) is maintained during the knitting of a horizontal stripe in the knitted fabric until a cam member 121 of a link of the timing chain acts again upon the cam follower 119 of the lever 117.

If, for example, the striping feeder 2 is to be exchanged for the heel yarn feeder 5, which operates during the knitting of the heel or toe (Figs. 19 and 20), a turning movement of the main control drum, not illustrated in the drawings, takes place as a result of an impulse derived from the timing chain, whereby the lever 71 of the coupling 72 is caused to turn from its position IX into the position X, as shown in Fig. 22. The bent end 69 of the member 70 pushes against the bevelled portion 68 of the guide plate 60, thereby causing vertical and lateral displacement of the latter from the position XI (Fig. 11) into the position XII (Fig. 18). As a result, the adjusting pin 57 of the change-over member 49 is caused, by the inclined slot 59 of the guide plate 60, to move from the position XIII, shown in Figs. 10 and 11, into the position XIV shown in Fig. 18. In the position XIV, the upper projection 52 of the change-over member 49 of the cam

member 50 is engaged in the circular recess 54 of the upper selecting lever 48 (Fig. 9), thus coupling together the members 49 and 50 and the lever 48. The bottom projection 51 of the change-over member 49 is free to move inside the oblong recess 55 of the bottom selecting lever 34 (Fig. 7) without affecting the latter, so that the selecting drum 32 remains in its rest position XV which is remote from the selecting pins 21 (Fig. 20) during the heel or toe knitting, and it cannot then be brought into action.

During the lateral pivotal movement of the lever 71 of the coupling 72 from the position IX into the position X (Fig. 22), the actuation of the lever 78 by the grooved cam drum 90, described above, is repeated, and is initiated by a cam member 121 of a chain link 120 acting upon the cam follower 119 of the lever 117. As a result of the lateral pivotal movement of the lever 78 from the position O (Fig. 19) into the position P (Fig. 20), the roller 80 moves along the cam face 81 of the cam member 50, thereby causing the upper selecting lever 48 together with the arm 46 to turn about the pivot pin 35 of the bracket 36 from the position XIX (Fig. 19) into the position XX (Fig. 20). The arm 46 of the lever 48 pushes the selecting pin 21 associated with the heel yarn feeder 5 and causes the feeder 5 to swing laterally from the rest position I into the intermediate position II. The further steps for replacing the feeder 2 (Figs. 19, 20) by the heel yarn feeder 5 are the same as described above in connection with the interchanging of the feeders 2 and 3 (Figs. 13 to 17).

In order to make possible the use of the same striping feeder, for example, the feeder 2, before and after the operation of the heel yarn feeder 5, it is necessary to prevent the tooth 41 of the actuating pawl 42 from engaging the ratchet wheel 39 of the selecting drum 32 (Fig. 19). This is achieved in such a manner that, when the lever 71 of the clutch 72 moves from the position IX into the position X (Fig. 22) and the lever 210 is shifted from the position XVII into the position XVIII, the bent end 214 of the lever 210 engages the longer arm of the double-armed lever 215 (Fig. 18) and turns the latter about the pivot screw 216 into the position XXII wherein the shorter arm of the lever 215 engages the extension 44 of the actuating pawl 42 and moves the latter in a direction away from the ratchet wheel 39 (Figs. 19 and 20). This position of the actuating pawl is maintained up to the exchange of the heel yarn feeder 5 for the feeder 2. When the feeder 2 is subsequently moved from the position I into the position II (Fig. 12) and the simultaneous pivotal movement of the bottom selecting lever 34 causes the selecting drum 32 to move in a direction towards the selecting pins 21, turning movement of the selecting drum 32 about its spindle 33, which would otherwise occur, is avoided. For this reason, action of the actuating pin 38 of the selecting drum 32, which existed before the heel or toe knitting, remains effective. When the selecting drum 32 approaches the selecting pin 21, the tooth 218 of the lever 215, being in the position XXII (Fig. 18), slides along the extension 44 of the actuating pawl 42, and before the pin drum 32 reaches its end position XVI (Fig. 12), the tooth 218 of the lever 215 leaves the extension 44 of the actuating pawl 42. Gravity causes the double-armed lever 215 to again assume a vertical position XXI (Fig. 11) unimpeded by the bent end 214 of the lever 210 which is again in its position XVII (Figs. 11 and 22). In this manner, the tooth 41 of the actuating pawl 42 reengages the ratchet wheel 39.

If it is desired to interchange the individual feeders, for example, in the sequence 4, 3, 2, 1, the actuating pins 38 have to be arranged stepwise in the selecting drum as illustrated in Fig. 8, so that by the progressive intermittent rotation of the selecting drum 32 in the direction indicated by the arrow, a continuously repeated exchange of the feeders is achieved in the stated sequence.

For any other sequence of operation of the individual feeders, for example, in the sequence 4, 1, 2, 3, it should be necessary to alter the positions of the actuating pins 38 in the selecting drum 32. In order to avoid this, that is, in order to permit the use of a previously set arrangement of the actuating pins 38 for any subsequently required feeder exchange, the control mechanism G for the selecting drum 32 (Figs. 21 and 22) may be used. For this purpose, chain links 125 and 127 with the lateral studs 126 and the chain links 120 with the cam members 121 (Fig. 27) are arranged in a certain sequence to from the actuating chain. Thus, for example, a cam-member 121 of a chain link 120 imparts an impulse for moving the feeder 4 into the operational position. The cam-member 121 of the succeeding chain link 120 would produce an impulse for moving the feeder 3 into operational position. If, however, it is desired that the operation of feeder 1 should follow the operation of feeder 4, a chain link 137 with two lateral studs 126 (Fig. 27) is inserted with such studs producing an impulse which causes the selecting drum 32 to turn through an angle corresponding to two tooth pitches of the ratchet wheel 39. The cam follower 128 of the lever 129, when it is displaced by the first lateral stud 126 of the chain link 127, causes a pivotal movement of the lever 129 as well as a shifting of the connecting rod 131, lever 134, tie-rod 136 and lever 137 (Figs. 21, 22). The free end of the lever 137 engages the extension 139 of the nut 140 of the selecting drum 32, thus causing the drum 32 and the ratchet wheel 39 to be turned through one tooth pitch, as the actuating pawl 42 is in engagement with the ratchet wheel 39. This arrangement replaces the action of the roller 80 of the lever 78 upon the cam member 50 and the bottom selecting lever 34. The exchange of the feeder 2 for the feeder 1 is effected by means of the other lateral stud 126 of the chain link 127 (Fig. 27). By means of this chain link 127 interposed between chain links 120, it is possible to obtain any required feeder sequence after knitting four to six courses.

The above described control of the selecting drum 32 by the use of chain links 125 and 127 with lateral studs 126 can be employed for the knitting of any portion of hosiery, provided the pawl 42 is in engagement with the ratchet wheel 39 of the drum 32. The control mechanism G for the selecting drum 32 can be used to advantage if all available feeder changes are not required for the knitting of a whole sock or stocking. In this manner the choise of one and the same feeder as well as of one and the same color of the courses at the beginning of the knitting is secured.

I claim:

1. A circular knitting machine for automatically manufacturing hosiery goods having course-wise striping comprising at least one rotary needle cylinder, a plurality of interchangeable yarn feeders each having a feeding eye at one end thereof, all of said yarn feeders being normally arranged in a first plane substantially radial to the axis of rotation of said needle cylinder with the longitudinal axes of said yarn feeders converging toward a knitting point adjacent the circumference of said needle cylinder, a support having slots guiding said feeders for lengthwise movement of each feeder as well as for pivotal movement of each in a second plane which extends through the longitudinal axis of the feeder and is disposed at right angles to said first plane, a return spring acting on each feeder and urging the latter longitudinally to a rest position remote from said knitting point, a spring biased holding pin corresponding to each of said feeders, each of said feeders having a lateral recess located for engagement by the corresponding holding pin when the feeder is moved to an operative position in which said feeding eye of the feeder is disposed at said knitting point so that said holding pin then maintains the feeder at said operative position, each of said feeders

further having a longitudinal slot therein, a pivot pin extending through said longitudinal slot of each feeder with the axis of said pivot pin being perpendicular to said second plane of movement of each feeder, a selecting pin associated with each feeder and movable against the latter at a point along the feeder between said pivot pin and said feeding eye to angularly deflect the feeder about said pivot pin in said second plane, a thrust member engageable with the other end of each feeder remote from said feeding eye when the feeder is deflected by said selecting pin and effective to shift the engaged feeder in said second plane towards said needle cylinder, said return spring and spring biased holding pin for each feeder yieldably resisting the deflection of the latter by said selecting pin, means for withdrawing the holding pin from said lateral recess of a feeder at said operative position thereby to permit said return spring to return the feeder from said operative position to said rest position, and control means effective, after the withdrawal of said holding pin from the recess of a feeder at said operative position, to release the selecting pin from another selected feeder which has been deflected thereby and shifted by said thrust member so that the spring biased holding pin and the return spring associated with 25 said selected feeder can then swing the latter about said pivot pin into the operative position of the selected feeder.

2. A circular knitting machine as in claim 1, wherein said control means includes a selecting member movable toward and away from the selecting pins associated with 30 said feeders, and means for operatively connecting said thrust member and said selecting member to cause the latter to move toward the selecting pins during an initial portion of an operative stroke of said thrust member toward the feeders so that the selecting pin associated 35 with a selected feeder deflects the latter to bring said other end of the selected feeder into the range of said thrust member and, thereafter, during further movement of the thrust member, the latter shifts the deflected feeder toward said needle cylinder, and to cause said selecting 40 member to move away from said selecting pins so that the selected feeder can swing back, under the influence of the associated return spring and holding pin, to assume said operative position during the return stroke of said thrust member in the direction away from the feeders;

45 and wherein said thrust member engages and actuates said means for withdrawing the holding pin from the recess of a feeder in said operative position during said shifting of the selected feeder by the operative stroke of the thrust member.

3. A circular knitting machine as in claim 2, wherein said thrust member is common to all of said feeders and has an arcuate thrust plate the curvature of which is substantially the same as that of an arc along which said other ends of the converging feeders lie when the latter 50 are in their rest positions.

4. A circular knitting machine as in claim 2, wherein said means for withdrawing the holding pins from engagement in the recesses of the corresponding feeders when the latter are in the operative positions thereof 55 includes a movable pin withdrawing member common to all of the holding pins, spring means urging said withdrawing member to an inoperative position releasing said holding pins for engagement with the related feeders, said withdrawing member being movable by said thrust member to an operative position where it withdraws all of said holding pins during a final portion of the operative stroke of said thrust member in the direction for shifting a selected feeder toward the needle cylinder, said withdrawing member being released by said thrust member 60 for return to said inoperative position during an initial portion of the return stroke of said thrust member in the direction away from said feeders.

5. A circular knitting machine as in claim 2, wherein said selecting member is common to all of the selecting pins associated with the feeders to be used during course-

wise striping and is in the form of a rotatable drum having a plurality of faces, each of said faces having radially opening bores corresponding in number to the number of selecting pins which are to be controlled thereby, each of said bores being dimensionally adapted to receive the end of a related one of said selecting pins when said selecting member is moved toward the latter to avoid shifting of the selecting pins which enter said bores, and an actuating pin in one of said bores to prevent the entry into said one bore of the corresponding selecting pin so that the latter is shifted to deflect the corresponding feeder when said selecting member is moved toward the selecting pins.

6. A circular knitting machine as in claim 5, further comprising means for effecting step-by-step rotation of said drum so that, during each movement of said selecting member toward the selecting pins, another of said faces of the drum faces toward said selecting pins to determine which of the latter is to be shifted.

7. A circular knitting machine as in claim 6, wherein said means for effecting step-by-step rotation of the drum includes a pawl and ratchet device which, in response to each movement of said selecting member toward the selecting pins, turns said drum through an angle subtended by one of said faces thereof.

8. A circular knitting machine as in claim 5, further comprising a cam-operated mechanism operatively connected to said drum of the selecting member for turning said drum so that any of said faces of the latter can be selectively turned to face toward said selecting pins during the movement of said selecting member toward the selecting pins.

9. A circular knitting machine as in claim 2, wherein said selecting member is common to all of the selecting pins associated with those feeders to be used during course-wise striping; and further comprising an additional selecting member movable independently of the first mentioned selecting member toward and away from the selecting pin associated with a feeder which is inoperative during course-wise striping, said means for operatively connecting thrust member and said selecting member being effective to alternatively connect said first selecting member and said additional selecting member with said thrust member.

10. A circular knitting machine as in claim 9, wherein said means effective to alternatively connect said first selecting member and said additional selecting member with said thrust member includes change-over means arranged between said selecting members to selectively determine which of the latter is operatively connected with said thrust member.

11. A circular knitting machine as in claim 10, further comprising a lever carrying said thrust member, a cam-follower on said lever, and a cam member actuated by said cam follower, said change-over means being accommodated within said cam member.

12. A circular knitting machine as in claim 1, further comprising two yarn cutting devices for cutting the yarn knitted by the feeder which is returned from its operative position to its rest position and for cutting the beginning of the yarn of the selected feeder moved to its operative position, respectively, and means for operating said yarn cutting devices in response to actuation by movement of said thrust member.

13. A circular knitting machine for automatically manufacturing hosiery goods having course-wise striping, comprising a rotary needle cylinder, a plurality of in-

terchangeable yarn feeders each having a feeding eye at one end thereof, a support having slots therein accommodating said feeders with said feeding eyes of the latter directed towards said needle cylinder, said slots of the support having longitudinal axes which lie in a plane that is substantially radial to the axis of rotation of the needle cylinder and which converge toward a knitting point at the circumference of said cylinder, a pivot pin in said support lying in said plane and extending across each of said slots at right angles to said longitudinal axis of the related slot, each of said feeders having a longitudinal slot receiving said pivot pin so that each feeder is movable longitudinally toward and away from the needle cylinder and is also swingable about said pivot pin in a plane at right angles to the first mentioned plane, a return spring acting on each feeder and urging the latter longitudinally to a rest position wherein said feeding eye is remote from the knitting point and the longitudinal axis of the feeder lies substantially in said first plane, a spring biased holding pin for each feeder slideable in said support transversely with respect to said first plane and acting against a longitudinal edge of the related feeder between the other end of the latter and said pivot pin, each feeder having a lateral recess in said longitudinal edge which is located to receive the related holding pin when the feeder is shifted to an operative position in which said feeding eye is adjacent to said knitting point and said longitudinal axis of the feeder lies in said first plane so that said holding pin then resists the return of the related feeder from said operative position to said rest position by the related return spring, a selecting pin for each feeder slideable in said support transversely with respect to said first plane and engageable with said longitudinal edge of the related feeder between said pivot pin and said feeding eye so that, when said selecting pin is moved in the direction toward said first plane, the selecting pin angularly deflects the related feeder out of said first plane and such angular deflection of the feeder is yieldably resisted by the related spring-biased holding pin and return spring, a thrust member movable in operative and return strokes which are directed respectively toward and away from the needle cylinder, said thrust member being engageable, during its operative stroke, with said other end of any feeder which has been angularly deflected out of said first plane by the related selecting pin so that said thrust member moves the deflected feeder bodily toward the needle cylinder, a selecting member movable toward and away from the selecting pins and operative to displace a selected selecting pin toward said first plane during movement of the selecting member in the direction toward the selecting pins, operative connecting means between said selecting member and said thrust member effective to cause movement of said selecting member toward and away from the selecting pins during the operative and return strokes, respectively, of said thrust member, and withdrawing means effective to move said holding pins away from the related feeders during the final portion of said operative stroke of said thrust member and to release said holding pins for engagement with the related feeders during an initial portion of said return stroke of the thrust member.
